UNITED STATES PATENT OFFICE

JOHN TONGUE HUGHES, OF NEW YORK, N. Y.

DEVICE FOR ELEVATING LINES

Application filed May 3, 1928. Serial No. 274,954.

The present invention is directed to a device for elevating lines upon which various articles or devices may be suspended.

One of the objects of the invention is to provide a device of this kind which is admirably adapted for use in yards for drying clothes, the construction being such that the line can be elevated in order that persons can pass under the clothes suspended on the line and children can play in the yard without touching the clothes.

Another object of the invention is to provide a device of this character so constructed that articles, such as wearing apparel can be supported upon the line for display purposes when the line is lowered and for storage purposes when the line is elevated, the device being particularly useful in establishments having high ceilings which will permit the line to be elevated to such heights that the articles thereon will be out of the way, but readily lowered when desired.

Another object of the invention is to provide a device of this kind designed for the advantageous display of merchandise of various kinds, and in fact for any purpose wherein it is desired to save space.

Another object of the invention is to provide means whereby a plurality of lines can be stretched for supporting articles.

While the drawings illustrate a preferred embodiment of the invention, it is to be understood that in adapting the means to meet specific needs and requirements the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which—

Figure 1 is a side view of the device.

Figure 2 is a sectional view on line 2—2 of Figure 1.

Figure 3 is a sectional view on line 3—3 of Figure 1.

Figure 4 is a detail sectional view of one of the wheel supporting frames;

Figure 5 is a sectional view on line 5—5 of Figure 4.

Figure 6 is a perspective view of one of the blocks, the associated parts being in proper position for assemblies.

Figure 7 is a detail view of one of the positions of adjustment.

Figure 8 is a diagrammatic view of a modified form of stretching the ropes for elevating the frames.

Corresponding and like parts are referred to in the following description and designated in the several views, of the drawings by like reference characters.

The device comprises a pair of upper and lower brackets 2 and 3, provided, respectively, with openings 4 and 5, in which are engaged the upper and lower ends of the guide rods 6, the upper ends of which are threaded in the outer ends of the upper blocks 7, as at 8, while the lower ends extend through openings 5 of the brackets 3 and have engaged thereon clamping nuts 9. The inner ends of the blocks 7 rest upon the upper brackets 2, there being lower blocks 10 which have their outer ends engaged upon the brackets 3, said blocks having openings 11 and in which the lower ends of the rods 6 engage. The outer ends of the blocks 7 and 10 are connected by guide rods 12 which have their ends threaded in the sockets 13 of the respective blocks.

It will be observed that the brackets can be secured in any appropriate manner to the posts in a yard, or to a post and building. It will be of course understood that the brackets can be secured to any suitable supports, the location thereof depending upon the purpose for which the line is to be used.

One of the upper blocks has carried upon opposite sides thereof hooks 14 and 15, while the other upper blocks have carried thereby oppositely located hooks 16, the purpose of which will be later explained.

The guide rods 6 and 12 are confined in the frames 17, said frames having axles 18 and 19 supported transversely therein and upon which are journaled grooved wheels 20 and 21, respectively, said wheels having their grooves engaged with the rods 6 and 12.

The confronting ends of the frames 17 have 100

carried thereby hooks 22 and to which are secured the ends of the main line 23, which may be in the nature of a rope or wire cable, as desired.

5 The frames 17 have fixed thereto yokes 24, one of which has connected thereto a sheave 25, while the other has connected thereto a sheave 26, and connected with one of the hooks 16 for alinement with the sheave 25 is 10 a sheave 27. Supported by the hook 14 are paired sheaves 28 and 29.

In order to control the raising and the lowering of the frames 17 and thus the line 23 two lengths of rope 30 and 30' are employed and 15 have their adjacent ends connected to a ring 31 to which is secured an anchor rope 32. The rope 30 has a stretch 33 secured to the hook 15 and is trained over the sheave 29, and is looped as at 34, to engage the sheave 25, while 20 the rope 30' is trained over the sheave 28 and leads to and over the sheave 27, and is looped, as at 34' for engagement with the sheave 26, and has its end secured to the hook 16 opposite the one which supports the sheave 27.

25 It will thus be seen that when the anchor rope 32 is pulled the loops will contract, thus drawing the frames 17 and line 23 upwardly and evenly to elevated position, the release of the rope 32 obviously lengthening the loops 30 to permit the same to move downwardly, the frames being effectively guided in their movements by the wheels 20 and 21 upon the rods 6 and 12, and the load being evenly distributed on the line. In order to eliminate 35 noise when the frames reach their lowermost position rubber pads 35 are provided and have their ends provided with kerfs 36 which open into the perforations 37 thereof, said kerfs permitting passage of the rods 6 and 12 40 into the perforations 37. The pads when applied rest upon the blocks 10 to prevent the frame from contacting therewith when lowered.

A pair of detachable cross bars 38 are employed when it is desired to suspend lines in 45 addition to the main line 23, said bars having central notches 38' for fitting the squared shanks of the hooks 22, there being openings 39 in said bars for engaging the bills of said 50 hooks, thus maintaining the bars interlocked with the hooks, but readily removable when it is desired to use only the main line 23. These bars have connected thereto in any approved manner a rope to provide additional lines 40. 55 As illustrated, a single length of rope is provided, but it will be of course understood that single strands may be employed if desired.

The bars 38 are only used when it is desired to suspend a comparatively larger number 60 of articles, and it is especially desirable when the device is used for drying clothes.

Adjacent the anchor rope 32 is fixed a cleat 41 to which the rope 32 can be secured to hold the frames and lines in selected elevated position. However, a drum or the like may be

used for elevating the frames should it be desired. The blocks 7 and 10 are capable of being swung laterally as shown in Figure 7, whereby they may be secured or supported in offset relation, so that the lines will be supported diagonally. 70

It will be obvious that upon tightening the nuts 9 the upper and lower blocks 7 and 10 will bindingly engage the brackets 2 and 3, respectively, thus holding the blocks in adjusted position. 75

The lower blocks 3 are mounted at points to support the line in a position to permit a person of average height to conveniently place articles thereon within reaching distance 80 when the line 23 is in its lowermost position.

From the foregoing description it will be seen that a device has been provided which may be used for drying clothes, suspending apparel or other articles, such as rugs for display, and may be used for suspending signs or the like at railroad crossings. 85

In Figure 8 a single pull line 41 is employed and has connected thereto ropes 42 and 43 which are connected directly to the frames 17 which support the line 44. Obviously when the line 41 is pulled the ropes 42 and 43 will be simultaneously pulled for elevating the frames 17, and thus the line 44. 90

Having thus described the invention, I 95 claim:

1. The combination with a pair of upper and lower brackets, of blocks engaged upon the brackets, guide rods connecting the blocks, one of said guide rods constituting 100 means for holding the upper blocks in binding engagement with associated brackets, frames slideable on the rods, a line stretched between the frames and having its ends connected with the frames, and means for simultaneously raising or lowering the frames, and thus the lines. 105

2. The combination with pairs of opposed upper and lower brackets, of blocks engaged upon the brackets, a pair of rods connecting the blocks of each pair, one rod of each pair having its upper end fixed in the associated upper blocks, means for tightening the rod to hold the upper blocks bindingly engaged in various positions of adjustment with the 110 respective brackets, a frame slideable on each of the pairs of rods, said frames having grooved wheels carried thereby for engaging the rods, a line stretched between the frames and having its ends connected to the 115 opposed ends thereof, and means for simultaneously raising or lowering the frames and thus the line. 120

3. The combination with pairs of opposed upper and lower brackets, of blocks engaged upon the upper brackets, blocks engaged upon the lower brackets, a pair of rods associated with the upper and lower blocks of each pair, one of said rods being fixed in the upper blocks of each pair, a nut upon the rod 125 130

for holding the upper blocks in binding engagement with the upper brackets, frames 5
slidable on the rods, a line stretched between the frames and having its ends connected thereto, and means for raising and lowering the frames, and thus the line.

4. The combination with pairs of upper and lower brackets, of blocks engaged upon the brackets, a pair of rods connecting the blocks, frames slidable on the rods, means 10
associated with one rod of each pair for holding the associated blocks in various angles of adjustment upon the associated brackets, a line stretched between the frames and having its ends secured thereto, and means for simultaneously raising and lowering the frames. 15

In testimony whereof I affix my signature.
JOHN TONGUE HUGHES. [L. s.]
